UNITED STATES PATENT OFFICE.

JOHN CHISKO, OF WAYMART, PENNSYLVANIA.

ARMORED HOOD FOR AUTOMOBILES.

1,147,607.

Specification of Letters Patent.

Patented July 20, 1915.

Application filed February 12, 1915. Serial No. 7,833.

To all whom it may concern:

Be it known that I, JOHN CHISKO, a citizen of the United States, residing at Waymart, in the county of Wayne and State 5 of Pennsylvania, have invented new and useful Improvements in Armored Hoods for Automobiles, of which the following is a specification.

The invention relates to armored vehicles 10 designed particularly for use in carrying rapid firing guns, whereby the guns may be quickly transported in any direction under motive power and the gunner and mechanician protected from the enemy's fire.

15 The primary object of the invention resides in the provision of an armored hood adapted to be supported upon the chassis of a highly powered motor car and capable of vertical adjustment whereby the hood 20 may be quickly lowered to the ground when the machine is stationary, and maintained at any desired degree of elevation while the car is in motion.

Another object of the invention is to provide 25 a traveling armored car or vehicle, provided with its own motive power, and forming an armored ambulant inclosure for the gunner, driver or mechanician, and which supports one or more rapid firing guns 30 which may be adjusted to a position for use and withdrawn to a protected position within the hood when not in use, the construction of the vehicle allowing advances to be made against the enemy in the field or 35 in trenches while the guns are maintained in action without exposing the gunner or driver.

Other objects of the invention will appear 40 from the following description when taken in connection with the accompanying drawing, the invention residing in the construction, combination and arrangement of parts hereinafter more fully described.

In the drawings forming part of this application like numerals of reference indicate 45 similar parts in the several views and in which:

Figure 1 is a side elevation. Fig. 2 is a top plan view. Fig. 3 is a horizontal sectional view. Fig. 4 is a transverse sectional view. Fig. 5 is a vertical sectional view.

Referring more particularly to the drawing 50 5 indicates generally a motor vehicle of usual construction. In carrying out my invention, the vehicle embodies an armored hood 6 preferably constructed of strong

sheet metal, its contour being similar to a huge turtle back shell, while the sloping sides tend to deflect the bullets or other projectiles out of their path of travel, thus protecting the car to a determined degree. The construction and arrangement of the hood define a protected compartment 7 for the gunner, motor 8, fuel tank 9, and the ammunition, etc. The hood is provided with an 60 opening 10 through which a gun deck or platform 11 is adapted to be projected for use, the deck or platform supporting a rotary carriage 12 upon which may be mounted one or more rapid firing guns 13, which 65 are projected for use when the deck is elevated and disappear or drop down within the hood and are concealed when the deck is lowered. Suitable gearing 14 is provided for raising and lowering the deck, the latter 70 being locked by means of the cam 14' in any desired position of adjustment, the opening being normally closed by a door 15. Suitable means may be employed for turning the rotary carriage 12 from within the 75 machine whereby the guns may be turned at an angle for use without the necessity of exposing the gunner.

To enable the driver to see in guiding the machine and locating the enemy, I employ 80 an instrument known as the "periscope." The instrument consists of a tube 16 of suitable length having a sight opening 18 adjacent the upper end thereof. Arranged within the tube directly in the rear of the 85 opening is a mirror 19, disposed at the proper inclination to reflect the image in advance of the sight opening, upon a second mirror arranged in the lower end of the tube, from which it is observed by the 90 driver. As shown the periscope projects through a restricted opening in the top of the hood, being vertically adjustable in the collar 20 and held in any desired adjusted position by means of the set screw 21. The 95 collar is rotatably mounted in the restricted opening of the hood, so that when the collar and periscope tube are fixed relatively, the latter may be turned to sight in any direction. The tube is preferably made in two 100 sections and capable of being readily detached to permit a new mirror, or an entirely new section containing the mirror to be substituted for the original one, should the latter be destroyed by bullets or the like 105 from the guns of the enemy. Any number of these mirrors or sections could be easily 110

carried in the machine for instance in the compartments 22 at the front and rear end of the hood, and wherein water and provisions may also be stored. A series of hook-like wire cutting elements 23 are secured to the outer surface of the hood, to prevent wire entanglements. A door 24 is also provided to permit ingress and egress to the machine.

10 The hood 6 is supported upon the chassis 25 for vertical adjustment, so that the hood may be lowered to the ground with a view of wholly protecting the various parts of the machine, when fighting therefrom, while 15 the machine is stationary. To this end suitable brackets 26 are secured to the longitudinal edges of the chassis adjacent each of the four corners thereof, for the reception of the uprights 27 which latter are adjustably mounted therein, and support the hood 6. Each of the uprights 27 has a rack surface 28 for meshing engagement with the gear wheels 29 carried on the opposite ends of the longitudinally disposed shafts 30, the 25 latter being arranged at the opposite sides of the machine. Fixed upon each of the shafts 30 is a bevel gear 31 operatively associated with a similar gear 32 fixed on the opposite ends of a transversely disposed shaft 33, whereby the shafts 30 are rotated upon rotation of the shaft 33, thereby raising or lowering the hood as the case may be. A pivoted lever 34 is arranged in convenient reach of the driver of the machine, and has 35 secured to its lower end a ratchet wheel 35 adapted to coöperate with a gear 36 fixed upon the shaft 33, whereby rotary movement is imparted to the latter when the lever is oscillated, the ratchet wheel being provided with the usual pawl 37.

Pivoted to the floor of the machine is a spring pressed foot operated dog 38 normally engaging the teeth of the ratchet wheel 35 to lock the shaft 33 against retrograde movement thereby maintaining the hood at any desired degree of elevation.

It is of course to be understood, that the hood is maintained in elevated position, only when the machine is in motion, as for instance when charges or advances are being made against the enemy, so that the hood will clear any obstructions disposed in the path of travel of the machine, as well as to permit the machine to travel speedily over irregular surfaces. But for stationary fighting the hood is lowered to the ground. In lowering the hood it is only necessary to depress the foot operated dog 38, moving the latter out of engagement with the ratchet wheel 35, whereupon the various shafts are free to rotate, and the hood under its own weight will instantaneously gravitate to its lowered adjusted position.

It will be understood from the foregoing description that a car or traveling military

vehicle is provided within which a gunner and operator may be contained and protected, and which carries one or more rapid firing guns which may be used without the gunner exposing himself. A vehicle of this kind is especially valuable in warfare for use as an armored road vehicle capable of traveling in any direction, or as a means by which the enemy in the field or entrenched may be charged and subjected to fire from a concealed and protected crew. A number of these vehicles running at a desired speed at certain intervals apart and keeping up a heavy fire as they advance toward the enemy will serve as an efficient attacking force without the necessity of employing a large body of men. Whenever necessary the guns may be lowered to protect them from the fire of the enemy, as in the travel of the vehicle to a certain position for opening fire, during retreat, or when the gun mechanism is temporarily out of order and requires repair.

While I have illustrated and described the preferred form or embodiment of the invention I desire to have it understood that such various changes in the construction and arrangement of parts may be resorted to when desired as fall within the scope of the appended claims.

What is claimed is:—

1. A motor vehicle for military service comprising a wheeled frame with its driving parts, brackets secured to the opposite sides of the frame, uprights movable vertically in said brackets and having a rack surface, an armored hood supported by said uprights, shafts arranged at the opposite sides of the frame, gears at both ends of said shafts for meshing engagement with the rack surfaces of said uprights to adjust the latter upon rotation of the shafts, and means for rotating said shafts.

2. A motor vehicle for military service comprising a wheeled frame with its driving parts, rack bars mounted on the opposite sides of the frame for vertical adjustment, an armored hood supported by said rack bars, longitudinally disposed shafts at the opposite sides of the frame, gears at both ends of the shafts for meshing engagement with said bars for adjusting the latter upon rotation of said shafts, an intermediate gear fixed upon each of said shafts, a transverse shaft having gears at both ends for operative association with the intermediate gears, and means for rotating said transverse shafts.

3. A motor vehicle for military service comprising a wheeled frame with its driving parts, rack bars mounted on the opposite sides of the frame for vertical adjustment, an armored hood supported by said rack bars and defining a protected compartment for the crew, longitudinally disposed shafts at the opposite sides of the frame,

- gears at the opposite ends of said shafts for meshing engagement with said rack bars for adjusting the latter upon rotation of said shafts, a transversely disposed shaft, bevelled gear connections between the longitudinally disposed shafts and said transverse shaft, a ratchet wheel fixed upon said transverse shaft, a lever, and a pawl carried by the lever for engagement with the ratchet wheel for rotating said transverse shaft when the lever is oscillated, whereby rotary movement is imparted to said longitudinally disposed shafts for the purpose specified.
- 5 10 15 20 25 30 35 40 45 50
5. A motor vehicle for military service comprising a wheeled frame with its driving parts, rack bars mounted on the opposite sides of the frame for vertical adjustment, an armored hood supported on said rack bars and defining a protected compartment for the crew, shafts at the opposite sides of the frame, gears carried at both ends of the shafts for meshing engagement with the rack bars, a transverse shaft, bevelled gear connections between the first mentioned shafts and said transverse shaft, a ratchet wheel fixed upon said transverse shaft, a lever, a pawl carried by the lever for engagement with the ratchet wheel for
- rotating the transverse shaft when the lever is oscillated, whereby rotation is imparted to the first mentioned shafts for adjusting said rack bars, and a foot operated dog normally engaging the teeth of said ratchet wheel to lock said shafts against retrograde movement thereby holding said hood in adjusted position.
5. A motor vehicle for military service comprising a frame with its driving parts, an armored hood supported upon said frame for vertical adjustment, said hood having an opening in the top thereof, a gun deck adjustably mounted within the hood and adapted to be projected through said opening, means for locking said deck in elevated position, a collar rotatably mounted within an opening in the top of said hood, a periscope tube adjustable through the collar and said top of the hood, and mounted for rotation within said hood, and means for locking said tube in fixed relation with said collar in adjusted position.
- In testimony whereof I affix my signature in presence of two witnesses.
- JOHN CHISKO.
